US0D1044178S

(12) **United States Design Patent** (10) **Patent No.:** **US D1,044,178 S**
(45) **Date of Patent:** **** Sep. 24, 2024**

(54) **BODY FOR SHOE MANAGEMENT APPARATUS**

(71) Applicant: **LG ELECTRONICS INC.**, Seoul (KR)

(72) Inventors: **Jaeyoung Kim**, Seoul (KR); **Bohyun Nam**, Seoul (KR); **Seunghyun Song**, Seoul (KR)

(73) Assignee: **LG ELECTRONICS INC.**, Seoul (KR)

(**) Term: **15 Years**

(21) Appl. No.: **29/842,900**

(22) Filed: **Jun. 16, 2022**

(30) **Foreign Application Priority Data**

Dec. 17, 2021 (KR) 30-2021-0060958

(57) **CLAIM**

The ornamental design for a body for shoe management apparatus, as shown and described.

DESCRIPTION

FIG. 1 is a front perspective view of the body for shoe management apparatus showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross-sectional view taken along line **8-8** in FIG. 2.

The broken lines depict portions of the body for shoe management apparatus that form no part of the claimed design. The dash-dot lines illustrate the location from which the section drawings are created and shown in FIG. 8. The dash-dot lines form no part of the claimed design.

1 Claim, 8 Drawing Sheets
